Application April 24, 1952, Serial No. 284,168

2 Claims. (Cl. 196—28)

Our invention relates to the desulfurization of petroleum distillates boiling in the diesel fuel range.

Competitive demands are subjecting diesel fuels to increasingly rigid requirements, particularly with respect to content of objectionable sulfur compounds, usually in the form of aromatic and aliphatic sulfur compounds, principally mercaptans, and total sulfur content. For example, the large increase in the use of high speed diesel engines, particularly by railroads, has led to the adoption by many railroads of a test for diesel fuels which is known as the St. Louis and South Western Railroad 500° F. Copper Strip Corrosion test. The test is sensitive to both elementary and disulfide sulfur and thus a fuel which passes a standard corrosion test at 212° F., which is sensitive to only elementary sulfur, may fail the 500° F. corrosion test because of the presence of disulfides. A fuel failing the 500° F. corrosion test may cause nozzle clogging in diesel engines. Thus to satisfactorily pass this test, mercaptan sulfur must be removed instead of merely converted to disulfides. However, the removal of objectionable aliphatic sulfur compounds does not appreciably lower the total sulfur content as aromatic sulfur compounds remain. Therefore, to meet satisfactorily competitive requirements the fuel must be treated to remove aromatic as well as aliphatic sulfur compounds. Aromatic sulfur compounds may be removed by treating the fuel with sulfuric acid but because of the high consumption of acid, high treating losses and sludge disposal problems, it is not commercially attractive.

We have found that treating a petroleum distillate boiling in the diesel fuel range by a combination two-stage process of contacting the distillate in the vapor phase at a temperature of about 600° to 700° F. with an adsorptive clay type catalyst, e. g., "Floridin" clay, a commercially available natural Florida fuller's earth, and treating the distillate in the liquid phase with liquid sulfur dioxide under extraction conditions effectively removes objectionable sulfur compounds and reduces total sulfur content to a level that satisfactorily meets competitive requirements. Moreover, we have found that unexpectedly high "Floridin" clay catalyst life is obtained in our combination process, e. g., over twice the life of other clay or bauxite catalysts in terms of barrels of fuel effectively treated per ton of catalyst used. We have further found that the "Floridin" clay contacting step can be carried out at substantially lower temperatures, e. g. about 100° F. to 150° F. lower, to produce an oil of a desirable mercaptan sulfur content than are required when other clays or bauxite are used. In addition to the advantage of substantial heat savings, this lower contacting temperature is particularly advantageous as there is less danger of cracking of the fuel which would result in decreased yields and a less desirable fuel. The resulting diesel fuel is substantially mercaptan and disulfide free, satisfactorily passes the 500° F. copper strip corrosion test, is of low total sulfur content and of improved color and cetane index.

According to a preferred method of operation of our invention, we contact in the vapor phase a petroleum distillate boiling in the diesel fuel range, e. g., about 350° to 650° F., with "Floridin" clay at a temperature of about 600° to 700° F. and at moderate pressures, e. g., about atmospheric to 50 pounds per square inch. The clay treated distillate is then cooled and treated in the liquid phase with liquid sulfur dioxide under extraction conditions. An oil raffinate is recovered and is a substantially mercaptan-free, low sulfur content, e. g., about 0.2

2

per cent, non-corrosive diesel fuel and is obtained in high yields, e. g., about 90 to 95 per cent. We have found that this particular sequence of treating results in substantial heat savings particularly in treating a hot distillate, such as a distillate obtained directly from a refining tower, as this heat content is utilized in the clay contacting step whereas the heat content would be lost if the distillate were first treated with sulfur dioxide under low temperature extraction conditions followed by reheating for the clay contacting step.

The process of our invention effectively removes objectionable mercaptan sulfur from and reduces total sulfur content of petroleum distillates boiling in the diesel fuel range to produce high yields of superior diesel fuels while effecting substantial cost savings in terms of catalyst life, catalyst cost and heat requirements.

The adsorptive clay type catalyst useful in the process of our invention is "Floridin" clay which is a commercially available natural Florida fuller's earth composed chiefly of the minerals attapulgite and montmorillonite, with a dominant attapulgite content. We have found that fresh "Floridin" and spent "Floridin" are equally effective and display the same surprisingly superior catalyst life. By spent "Floridin," we mean "Floridin" that has been used in a refining process such as the adsorptive decolorizing of lubricating oil. Therefore, in addition to the cost savings due to increased catalyst life a cost saving is realized in the use of spent "Floridin" clay.

The petroleum distillates that are effectively treated by the process of our invention are distillates boiling in the diesel fuel range, e. g., about 350° to 650° F., and may contain relatively high amounts of sulfur.

The preferred method of operation of our invention is illustrated in Figure 1 which is a schematic flow diagram of a two-stage process of "Floridin" clay contacting followed by sulfur dioxide extraction.

In the drawing, a petroleum distillate boiling in the diesel fuel range is introduced by line 1 to heater 2 where it is heated to about 600° to 700° F. The heated oil is passed by line 3 to reactor 4 where it is contacted in the vapor phase with a fixed bed of "Floridin" clay. The distillate is contacted with the clay at a rate of about 8 to 12 barrels of liquid oil per ton of clay per hour. Moderate pressures are used, e. g., from about atmospheric to 50 pounds per square inch. Operating conditions are selected so that substantially no cracking of constituents other than the sulfur compounds results. The clay-treated distillate is withdrawn by line 5 and passed to steam stripper 6 where it is treated with steam to remove hydrogen sulfide and light ends which are removed by line 7. The stripped clay-treated distillate is then passed by line 8 to cooler 9 and by line 10 to extraction tower 11. In the extraction tower 11, the oil is contacted with liquid sulfur dioxide introduced by line 12 under extraction conditions. The extraction is carried out at temperatures in the range of about 80 to —20° F. and at solvent to oil ratios of about 0.5 to 2 volumes of sulfur dioxide per volume of oil. An extract containing aromatic compounds is removed by line 13. An oil raffinate is removed by line 14, neutralized with caustic solution and the resulting oil is a substantially mercaptan-free, low sulfur-content, noncorrosive diesel fuel and is obtained in high yields, e. g., about 90 to 95 per cent.

While the above treating sequence is preferred for large scale commercial operation as substantial heat savings are realized in treating a hot distillate in this sequence, a reverse sequence, e. g., initial sulfur dioxide treating followed by "Floridin" clay contacting, may be advantageous under certain conditions as initial sulfur dioxide treating removes some of the aliphatic sulfur compounds and as less sulfur remains to be removed by the "Floridin" clay, a further increase in catalyst life is obtained.

The superiority of the process of our invention is illustrated in Figure 2. The figure shows graphically the relationship between the temperatures required in a "Floridin" clay contacting step to maintain a desirable mercaptan sulfur level in the treated product and the catalyst life in barrels of oil effectively treated per ton of catalyst. Similarly, this relationship is shown for Olmsted clay and bauxite. The figure shows that when

using fresh or used "Floridin" clay catalysts, only near the end of the contacting step was it necessary to raise the temperature above 650° F. to maintain a desirable mercaptan sulfur level. However, Olmsted clay required a temperature of 750° F. at 1000 barrels per ton catalyst life and it was necessary to raise the temperature to 800° F. shortly after. The bauxite catalyst was not much better, requiring a temperature of 750° F. at 1500 barrels per ton catalyst life. This clearly indicates the uniqueness of "Floridin" clay catalysts.

The process of our invention will be further illustrated by the following examples.

Example I

A sour West Texas heating oil having a boiling range of 350° to 645° F. and an API gravity of 36.4 was treated in separate tests with Olmsted clay, bauxite, used "Floridin" clay and fresh "Floridin" clay.

The results were:

	Feed	Products			
		Olmsted Clay, 16-30 mesh	Bauxite	Used Floridin Clay, 16-30 mesh	Fresh Floridin Clay, 16-30 mesh
Catalyst.....					
Operation:					
Feed Rate B./T./Hr.....		11-60	10.7	11.25	10.96
Temp., °F.....		600-800	700-750	600-700	600-700
Catalyst Life, B./T.....		1,842	2,162	4,553	4,496
Oil Recovered, Wt. Percent.....		99.19	98.6	97.6	99.3
Inspection:					
Mercaptan Sulfur, Mg./100 cc.....	61.2	6.8	4.98	2.0	2.8
Total Sulfur, Wt. Percent.....	0.78	0.58	0.57	0.61	0.61
500° F. Cu. Strip Corrosion Test.....	Fail	OK	OK	OK	Fail

The results show that mercaptan sulfur was reduced from 61.2 in the sour feed stock to 2 to 2.8 milligrams per 100 cc. in the treated distillate by the use of used or fresh "Floridin" clay while Olmsted clay and bauxite show a reduction to only 6.8 and 4.98 mg./100 cc. respectively. The total sulfur content reduction was at least equal to the mercaptan sulfur removed. In addition to this more effective mercaptan removal, the "Floridin" clays produced an average of 4524 barrels of oil per ton of catalyst while the Olmsted clay and bauxite produced only 1842 and 2162 barrels per ton respectively, an average of 2.25 times as great as the conventional catalysts clearly indicating the superior effectiveness of the "Floridin" clays. Moreover, fresh "Floridin" clay produced a slightly higher yield than bauxite or Olmsted clay.

The product obtained by the use of used "Floridin" clay passed the 500° F. Copper Strip Corrosion test. While the product obtained by the use of fresh "Floridin" clay did not pass the test, the failure is not considered serious since in commercial operations the mercaptan content could be controlled, by employing proper temperature, and kept to a low enough level so that even though disulfides were eventually formed their concentration would not be harmful.

Example II

The product of treating the sour West Texas heating oil of Example I with used "Floridin" clay was treated

with sulfur dioxide to remove aromatic sulfur compounds. The data were:

5	"Floridin" Treated Product	SO ₂ Treat (Raffinate)
Operation:		
Temperature °F.....		0
Solvent: Oil Ratio.....		2:1
Yield, Vol. Percent.....		91.6
Inspection:		
Mercaptan Sulfur, mg./100 cc.....	0.5	0.0
Total Sulfur, Wt. Percent.....	0.6	0.21
500° F. Cu. Strip Corr.....	OK	OK
Color, NPA.....	2½	1

The results show that by combining "Floridin" clay contacting with sulfur dioxide treating a product is ob-

tained that is mercaptan-free, of low total sulfur content and of improved color.

We claim:

1. A two-stage process for desulfurizing petroleum distillate fuels which comprises contacting a petroleum distillate boiling in the diesel fuel range in the vapor phase with the "Floridin" clay at a temperature of about 600° to 700° F. and treating the distillate in the liquid phase with liquid sulfur dioxide under extraction conditions and recovering a substantially mercaptan-free, low sulfur-content diesel fuel.

2. A two-stage process for desulfurizing petroleum distillate fuels which comprises contacting a petroleum distillate boiling in the diesel fuel range in the vapor phase with "Floridin" clay at a temperature of about 600° to 700° F., withdrawing a clay-treated distillate, treating the clay-treated distillate in a second stage in the liquid phase with liquid sulfur dioxide under extraction conditions and recovering a substantially mercaptan-free, low sulfur-content diesel fuel.
